UNITED STATES PATENT OFFICE.

BYERS W. KADEL, OF BALTIMORE, MARYLAND.

SIDE FRAME.

Application filed March 29, 1926. Serial No. 98,189.

This invention relates to side frames for railway car trucks and especially to such frames having journal boxes integral therewith.

5 The principal object of my invention, generally considered, is the provision of cast integral side frames in which the members thereof are designed with respect to their cross sections and arranged with respect to 10 each other so that great strength in proportion to the weight thereof is secured.

An object of my invention is the provision 15 of a cast side frame for railway car trucks in which the members thereof are so designed and the sections thereof are so varied that the most economical cross sections are employed in the various positions on the frame, and, for that purpose, the cross section of at least one of said members changes 20 both in strength and form between the ends thereof whereby the frame is lightened without sacrificing necessary strength and convenient making of the mould for the frame and positioning of the cores therein is provided for.

Another object of my invention is the provision of a cast side frame for railway car trucks formed with a compression member, the intermediate portion of which is preferably channel shape with an upper web and depending flanges on either side thereof and the end portions of which are gradually changed to I or T shape, a tension member, the central portion of which is box shape 35 and preferably formed with a central or intermediate upright web and the end portion of which are formed substantially + or star shape in cross section, the upright web of said star section, however, being preferably provided with transverse flanges at the upper and lower edges thereof.

A further object of my invention is the provision of a cast side frame for railway car trucks formed with compression, tension 45 and bolster column members, said bolster column members spacing intermediate portions of the compression and tension members and merging therewith, said frame being formed with a bolster opening framed by said members, the compression member above the bolster opening being formed channel shape in cross section, the tension member beneath the bolster opening being preferably box or double box shape in cross

55 section, the bolster columns being preferably T shape in cross section, said compression member uniting with the tension member and with journal boxes at the ends of the frame, said frame being preferably I or T section above the journal boxes, the portions 60 of the tension member diagonally disposed between the journal boxes and the lower corners of the bolster opening being formed for portions of their length by continuing the section under the bolster opening, said 65 section, however, being reinforced by ribs or T sections rising from the upper web of the box section.

A still further object of my invention is the provision of a cast side frame for railway car trucks formed with compression and tension members and bolster column or strut members spacing intermediate portions thereof, said tension member being formed substantially box shape in cross section 70 where it joins the lower portions of the bolster columns, which box section preferably extends outwardly and upwardly beyond said bolster columns with the side webs of said box section terminated before the 75 tension member reaches the journal boxes, an intermediate upright web being provided extending from journal box to journal box as part of the section of the tension member, the ends of said web, where it joins the journal boxes, being preferably bifurcated and connected to said journal boxes approximately at the junctions between the inner walls thereof and the inner brass lugs, the upper web of the box section, beneath the 80 bolster opening, being continued as an intermediate transverse web of the diagonal end portions of the tension member and extended to the journal boxes.

Other objects and advantages of the invention relating to the specific arrangement and combination of the various parts will become apparent as the description proceeds.

Referring to the drawings illustrating my invention, the scope whereof is defined by 100 the claims:

Figure 1 is a side elevation of a cast side frame for railway car trucks embodying my invention, a portion of said frame being shown in vertical section.

Figure 2 is a plan of the side frame shown in Figure 1, shown partly in section on the line 2—2 of Figure 1.

Figure 3 is a vertical cross sectional view on the line 3—3 of Figure 1 looking in the direction of the arrows.

Figure 4 is a vertical cross sectional view on the line 4—4 of Figure 1 looking in the direction of the arrows.

Figure 5 is a fragmentary sectional view on the line 5—5 of Figure 1 looking in the direction of the arrows.

10 Figure 6 is a fragmentary sectional view on the line 6—6 of Figure 1.

Figures 7 and 8 are detail sectional views on the correspondingly numbered lines of Figure 1.

15 Referring to the drawings in detail, like parts being designated by like reference characters, there is shown a cast side frame 1 which, in the embodiment illustrated, comprises a compression member 2, a tension member 3, bolster column guide or strut members 4 and journal boxes 5. The compression and tension members unite at the ends thereof and the journal boxes 5 are preferably integrally connected thereto at 20 the ends of the frame. Intermediate portions of the compression and tension members are spaced by the bolster guide members 4 which are shown as integral therewith.

25 30 The various frame members are preferably formed, as illustrated, of varying cross sectional configuration in order to secure economy of material without sacrificing the requisite frame strength. In the present embodiment, the compression member 2, over the bolster or window opening 6, formed between the compression, tension, and bolster guide members, is formed of inverted U shape or as a channel with an upper web 7 and depending flange portions 8. The lower edges of said flange portions are preferably formed with inwardly extending ribs or beading 9, as shown most clearly in Figure 3.

35 40 After extending beyond the bolster guides 4 and a portion of the distance between said guides and the journal boxes, the cross section of the compression member preferably changes gradually so that, over the journal boxes, the section is substantially T shape 45 with an upper flange 10 curved downwardly and meeting the roof 11 of the journal box substantially in line with the outer brass lug 12. That is, the upper edge, which changes from a web 7 to a flange 10, slopes 50 from a horizontal to substantially a vertical position where it joins with the journal boxes 5.

55 The web 13 of the T or I section, over and adjacent the journal boxes, merges with the roof 11 of each journal box, as illustrated. During the transition from a channel to an I or T section, the depending flanges 8 of the compression member gradually converge and finally unite to form the web 13, 60 the upper portion or web 7 thereof becoming

ing the flange 10 without other radical change although it preferably tapers slightly toward its ends to near the connections with the journal boxes where it flares slightly, as illustrated particularly in Figures 2 70 and 4. The lower beads or ribs 9 of the flanges 8 merge with the bolster columns 4 at the junctions of said columns with the compression member, and, as the inner flanges of said columns are bent outwardly 75 and form a lower web or wall of said compression member, said beading 9 may be considered as changing at the bolster columns into a lower web of said compression member thereby forming box sections for 80 portions of the length thereof.

85 It will be apparent that the compression member, in changing from a channel to an I or T section, passes through a stage in which it is first a box section and then a smaller box section with the upper web thereof extended beyond the side walls, that is, it has two webs, an integral upper flange and a lower wall joining the webs. Where the webs 8 unite, the lower wall formed by 90 the merging of the beads 9 is replaced by a flange 14 which is curved downwardly and inwardly to form or merge with the upper flange of the diagonal end portions of the tension member 3.

95 The tension member 3, beneath the bolster opening 6, is formed substantially box shape in cross section, as illustrated particularly in Figures 3 and 6, the upper web 15 of which, however, extends outwardly beyond 100 the side webs 16, as shown particularly in Figure 3, so as to form an adequate support for the spring plank, not shown, and the supported springs. The lower edges of the webs 16 are preferably joined by a trans-

verse web 17 preferably paralleling the upper web 15. In addition to the upright side webs 16, the tension member is preferably reinforced by an intermediate, preferably centrally disposed, upright web 18 which 105 divides the box section in two and securely rigidifies the upper and lower webs thereof with respect to each other. As additional reinforcing means, the extended or flange portions of the web 15 beyond the side webs 110 16 are preferably rigidified with respect to said webs 16 by transversely extending substantially triangular web or gusset portions 115 19, as shown most clearly in Figures 1 and 3.

120 To facilitate coring the spaces between the webs 15, 17, 16 and 18, a central aperture 20 is preferably provided in the web 15, and the intermediate web 18, beneath said aperture is reduced in depth, as illustrated most clearly in Figure 3. The edges of said aperture 20, as well as the upper edge of the web 18 beneath said aperture, are reinforced by beading 21 so that the strength of the section is not substantially decreased by the aperture 20. The box sections formed by 125

the webs 15, 16, 17 and 18 may be provided with drainage openings, as indicated at 22, if so desired. The aperture 20 may, if desired, also serve as means for properly positioning the spring plank, not shown.

The main portions of the tension member formed by the webs 15, 16, 17 and 18, as heretofore described, are preferably bent upwardly beneath the bolster columns 4 and 10 continued for portions of the distance between said columns and the journal boxes 5 except that the upper web 15 is preferably decreased in width, as indicated most clearly in Figures 2 and 6, as well as the other webs 15, 16, 17 and 18. The bolster columns 4, in the embodiment illustrated, are shown substantially T shape in cross section with inner transverse flanges 23 and longitudinal flanges 24, preferably beaded at their outer 20 edges, as indicated at 25. The flanges 24 are widened at the lower ends thereof and merged with the upper surface of the diagonally extending portions of the web 15 where they are continued therealong as upwardly 25 extending reinforcing flanges or webs 26, the beading 25 being likewise continued and extended as upper flanges or beading 27 along the upper edge of the tension member where, at their outer ends, they merge with the 30 downwardly extending beading 14 on the compression member at the outer corners of the substantially triangular openings 28.

Intermediate the bolster columns 4 and the journal boxes 5, the side webs 16 are discontinued, as illustrated in Figure 1, thereby transforming the main portion of the tension member from box to I shape in cross section, as illustrated most clearly in Figures 6 and 8. On account of the reinforcing web 40 26 and upper flange 27 thereto, the complete section, however, becomes + or star shape and, as illustrated in Figure 8, has upper and lower flanges at the corresponding edges of the vertical web 18—26. The distance 45 from the center line of the side frame, at which the side webs 16 are discontinued, may be in accordance with the particular design of frame, as desired. In the particular embodiment contemplated, however, it is intended that these webs be continued to approximately 16 inches from the center line 50 of the frame and this distance preferably corresponds with the distance at which the compression member starts to change from box to I or T shape in cross section. In the embodiment illustrated, the web 15 is continued straight from the lower corners of the bolster opening to points adjacent the journal boxes where it is bent upwardly at 55 an angle and joins with said journal boxes adjacent the roofs thereof. The lower web 17 is likewise extended but converges slightly toward the web 15 and, at a point corresponding approximately to the upward bending of said web 15, the web 17, which

at this point is a flange because of the omission of the webs 16, together with its connected web 18 is bifurcated, as illustrated particularly in Figure 5, and continued to the journal boxes, joining therewith at approximately the junctions of the inner brass lugs 29 with the inner walls 30 of the journal boxes. This bifurcated or double construction, where connection is made with the journal boxes, gives great strength at 75 this point and, on account of the coincidence of the connection of the web 18 with the journal boxes and the brass lugs 29 thereof, coring at these points is facilitated.

The upper ends of the bolster guide columns 4 connect with the lower edges of the compression member 2, the inner flanges 23 of said bolster column preferably being bent outwardly and extended as a lower floor or web 31 of the compression member, as illustrated particularly in Figures 1 and 7, the inwardly extending beads 9 of the compression member being merged with said floor 31. The webs or outwardly extending flanges 24 are preferably flared upwardly, 90 as indicated in Figure 1, and merge with the lower web 31 of the compression member together with their beads or ribs 25.

Triangular reinforcing webs 32 are preferably provided between the roofs 11 of the journal boxes and the web 13 of the compression member, as illustrated most clearly in Figures 1, 2 and 4. Brake hanger brackets 33 are preferably formed extending inwardly from the inner depending flange 8 100 of the compression member 1, as shown most clearly in Figure 3.

From the foregoing disclosure, it will be apparent that I have devised an improved side frame in which the sections of the various members are varied in shape and strength to economically take the stresses which they are called upon to bear in service, whereby the weight of the frame may be reduced without deleteriously reducing the strength thereof. A frame of the foregoing design can be constructed to meet the requirements of the American Railway Association.

Having now described my invention, what I claim is:

1. A truck side frame comprising a tension member and journal boxes integrally connected at the ends thereof, the intermediate portion of said tension member being formed with intermediate and side upright webs joining with horizontal webs at their upper and lower edges, the end portions of said tension member being bent upwardly and continued diagonally outward to said journal boxes.

2. A truck side frame comprising members joined together and leaving a bolster opening therebetween, the lower one of said members being box shape beneath the bolster

opening and provided with an intermediate vertical web, said lower member being extended outwardly and upwardly to either side of said bolster opening and united with 5 journal boxes at the ends thereof, the upper and lower webs of said box section being continued to said journal boxes but the side webs of said box section being discontinued at points intermediate the bolster opening 10 and the respective journal box.

3. A truck side frame comprising a tension member formed with journal boxes at the ends thereof, said tension member being arranged substantially horizontal at the central portion thereof with end portions extended diagonally outward to said journal boxes, said end portions being formed with a transverse web and a plurality of webs extending downwardly from said transverse 15 web, certain of said downwardly extending webs being omitted for a portion of the length of said tension member.

4. A truck side frame comprising a tension member formed with a substantially 25 horizontal intermediate portion and diagonally disposed end portions, said end portions being formed with a transverse intermediate web from which depend a plurality 30 of webs connected at their lower edges for a portion of the length of said end portions, the outer of said depending webs being omitted for the remaining length of said end portions.

5. A truck side frame comprising a tension member having diagonally disposed end portions, the upper portions of which are generally T shape in cross section and the lower portions of which are formed generally box shape in cross section for a portion 40 of the length thereof and provided with an intermediate vertically disposed web, the remaining portion of said length having the side webs of the section omitted so that said section is generally inverted T shaped in 45 cross section.

6. A truck side frame comprising a tension member, a compression member, bolster guide columns interposed between intermediate portions of said members and leaving 50 a bolster opening therebetween, journal boxes at the ends of said frame, the tension member being formed with diagonal end portions having transverse web portions extending from the lower corners of the bolster opening to the roofs of the journal boxes, said web portions being formed with side and intermediate depending web portions extending from beneath the bolster opening toward the journal boxes, the outer 55 of said depending web portions being discontinued intermediate the bolster guide columns and journal boxes.

7. A truck side frame comprising a tension member, a compression member, bolster guide columns interposed between in-

termediate portions of said members and leaving a bolster opening therebetween, journal boxes at the ends of said frame, the tension member being formed with diagonal end portions having transverse web portions 70 extending from the lower corners of the bolster opening to the roofs of the journal boxes, said web portions being reinforced by a depending box section extending outwardly from the bolster opening toward the 75 journal boxes, the outer webs of said box section being discontinued intermediate the bolster guide columns and journal boxes leaving substantially inverted T sections outwardly of said box section, said box section being continued beneath the bolster opening.

8. A truck side frame comprising a tension member, a compression member, bolster guide columns interposed between intermediate portions of said members and leaving an opening therebetween, journal boxes at the ends of said frame, the tension member being formed with diagonal end portions having transverse portions extending from 85 the lower corners of the bolster opening to the roofs of the journal boxes, said web portions being formed with intermediate and outer depending webs extending from beneath the bolster opening toward the journal 90 boxes, said outer webs being discontinued intermediate the bolster guide columns and journal boxes, said intermediate depending web being continued to the journal boxes.

9. A truck side frame comprising a tension member, a compression member, bolster guide columns interposed between the intermediate portions of said member and leaving a bolster opening therebetween, journal boxes at the ends of the frame, the tension 100 member being formed with diagonally disposed end portions having transverse web portions extending from the lower corners of the bolster opening to the journal boxes, said web portions being formed with intermediate and outer depending web portions 105 extending along the tension member from a point intermediate one journal box and the adjacent bolster guide column to a point intermediate the other journal box and the adjacent bolster guide column, the intermediate depending web being extended from journal box to journal box, and upstanding intermediate longitudinal web portions being provided extending from the upper surface 110 of the transverse web portions of the tension member between each journal box and the corresponding bolster guide column.

10. A truck side frame comprising a tension member, a compression member, bolster guide columns substantially T shape in cross section interposed between intermediate portions of said members and leaving an opening therebetween, journal boxes at the ends of said frame, the tension member being 115 120 125 130

formed with diagonally arranged end portions having transverse web portions extending from the lower portions of the opening to the roofs of the journal boxes, said web portions being formed with depending webs extending from beneath the bolster opening toward the journal boxes and with upstanding central longitudinal web portions formed with transverse flanges at their upper edges, 5 said flanges being continued at their outer ends as lower flanges of the compression member and at their inner ends continued as outer flanges of the bolster columns.

11. A truck side frame comprising a tension member, a compression member, bolster guide columns interposed between intermediate portions of said members leaving a bolster opening therebetween, journal boxes at the ends of said frame, the tension member being 15 formed with diagonal end portions box shape in cross section along the lower portions thereof and inverted T shape in cross section along the upper or outer portions thereof and provided with an upstanding rib 20 along the upper surface of the box and inverted T shaped diagonal end portions.

12. A truck side frame comprising a tension member, a compression member, bolster guide columns interposed between intermediate portions of said members leaving a bolster opening therebetween, journal boxes at the ends of said frame, said tension member being formed with diagonal end portions comprising a main transverse web extending from beneath the bolster opening 30 diagonally upward and outward to points adjacent the journal boxes where it bends upwardly at an angle and connects with the upper portions of said journal boxes.

13. A truck side frame comprising a tension member, a compression member, bolster guide columns interposed between intermediate portions of said members and leaving a bolster opening therebetween, journal boxes at the ends of said frame, the tension member being formed with diagonal end portions provided with a main transverse web extending beneath the bolster opening and continued upwardly and outwardly to 45 the journal boxes, and substantially central and outer depending webs extending from between a journal box and the adjacent bolster guide column to between the other journal box and the adjacent bolster guide 50 column, the central depending web being

continued outwardly to points adjacent the journal boxes where it is bifurcated and connects with said journal boxes adjacent the junctions of the inner brass lugs with the inner side walls of said journal boxes. 60

14. A truck side frame comprising a tension member, a compression member, bolster guide columns interposed between intermediate portions of said members and leaving a bolster opening therebetween, journal boxes at the ends of said frame, the tension member being formed with upper and lower webs extending from a point intermediate a journal box and the adjacent bolster guide column to a point intermediate 70 the other journal box and the other bolster guide column, said webs being connected by intermediate and outer upright webs extending a distance corresponding with the upper and lower webs, the upper and upper 75 intermediate webs being continued outwardly and joined with the journal boxes.

15. A truck side frame comprising a tension member formed with an intermediate 80 substantially horizontal portion generally box shape in cross section, end portions extending diagonally upward from the intermediate portion, said end portions being generally star shape in cross section adjacent their outer ends. 85

16. A truck side frame comprising a tension member, a compression member, bolster guide columns interposed between intermediate portions of said members and leaving a bolster opening therebetween, the compression member, at the portion thereof over the bolster opening, being generally channel shape in section, with a transverse web and depending side walls, said walls, beyond the 90 bolster opening, being connected by a lower web formed as a continuation of corresponding portions of the bolster columns whereby said compression member becomes generally box shape in cross section, the side walls of 95 said compression member, beyond the bolster columns, gradually converging beneath the upper web thereof with said walls finally united to form upright web portions, continued to the journal boxes and merging 100 with corresponding web portions of the tension member. 105

In testimony whereof I affix my signature.

BYERS W. KADEL.
